UNITED STATES PATENT OFFICE.

NELSON E. SPRINGSTEEN, OF DETROIT, MICHIGAN.

WAGON-POLE.

SPECIFICATION forming part of Letters Patent No. 316,671, dated April 28, 1885.

Application filed March 18, 1885. (No model.)

To all whom it may concern:

Be it known that I, NELSON E. SPRINGSTEEN, of Detroit, in the county of Wayne and State of Michigan, have invented new and useful Improvements in Attachments to Wagon-Poles; and I do hereby declare that the following is a full, clear, and exact description thereof, reference being had to the accompanying drawings, which form a part of this specification.

This invention relates to new and useful improvements in the construction and operation of wagon-pole irons, or attachments to wagon-poles of that description in which neck-yokes are employed to support the end of the pole when in use.

The invention has for its object the prevention of the accidental displacement of the neck-yoke, thereby avoiding the accidental dropping of the pole, and to furnish means as well by which a leading-team may be attached to the end of the pole, as more fully hereinafter described.

Figure 1 is a vertical longitudinal section through the front end of the wagon-pole, showing the device in position to receive the neck-yoke ring. Fig. 2 is a similar figure showing the neck-yoke ring engaged with the tongue and locked against accidental displacement. Fig. 3 represents the front edge of the holdback-iron, showing the socket in the end thereof to receive the locking-bolt.

In the drawings, A represents the holdback-iron, which may be inserted and secured in the tongue in any of the known ways. This holdback-iron terminates at its free end in a socket, a. B is a semicircular plate, having a slot, b, cut therein, through which the bolt or pivot-pin c passes. C is a locking-bolt in the form of a curved hook projecting from and cast or formed, preferably, integral with the plate B. D is a recess to allow the plate and locking-bolt to partially rotate upon the pivot-pin c. These devices may be let into a wooden wagon-tongue, or they may be employed with a pole-socket, such as is usually secured to the front end of a light carriage-pole.

In practice the plate and locking-bolt are thrown into the position shown in Fig. 1 preparatory to engaging the neck-yoke with the tongue. As this is done the neck-yoke ring impinges against the projecting and cut-away part of the plate and forces it to partially rotate upon the pin, thereby throwing out the locking-bolt, the free end of which engages in the socket in the end of the holdback-iron, where the weight of the neck-yoke upon the then rear end of the plate will hold it in place. This forces the opposite and beveled end of the locking-bolt to rest upon the edge of the recess. A ring engaged with the locking-bolt will afford the means of securing a leading-team to the pole, and this additional team will draw down and forward, thereby tending to hold the pole more steady.

To remove the neck-yoke, the operator will push the plate slightly to the rear by so much as the length of the slot in the plate by pressing against the end of the locking-bolt near its junction with the plate, where the removal of the neck-yoke will cause the plate to partially rotate and assume the position shown in Fig. 1.

It will be noticed that there is no spring to compel the locking-bolt to perform its functions, but that gravity is relied upon, so as to compel the bolt to lock the parts together.

What I claim as my invention is—

1. In combination with a wagon-pole having a holdback iron or stop and a rotating hook constructed and arranged with a pivoted plate to engage with a socket in the end of said holdback-iron, substantially as and for the purposes described.

2. A wagon-pole attachment, consisting of a holdback iron or stop having a recess formed in its free end, a semicircular plate having an elongated slot and supported upon a pivot pin or bolt and carrying a locking-bolt, constructed and operating substantially as and for the purposes specified.

N. E. SPRINGSTEEN.
